FREDERICK A. SCHLOSSOW, OF DETROIT, MICHIGAN

AUTOMATIC AIR VALVE FOR HYDRO-PNEUMATIC TANKS

Application filed April 19, 1928. Serial No. 271,361.

My invention relates to an automatic air valve for hydro-pneumatic tanks and its purpose is to introduce a pre-determined volume of air along with water delivered to the tanks in order that the air under compression therein may not be exhausted from the tank through the gradual discharge of water from the latter.

While my valve may be employed in connection with hydro-pneumatic tanks generally, it has been especially designed for pressure tanks for the delivery of water for toilet purposes under control of a suitable flushing valve.

With the foregoing and other objects in view which will appear as the description proceeds, the invention further resides in the combination and arrangement of parts and in the details of construction herein after described and claimed, it being understood that changes may be made in the precise embodiment of the invention herein disclosed without departing from the spirit of the same.

In the drawings accompanying this specification:

Figure 1 is a diagrammatic view partly in perspective and partly in section, showing piping leading from a water system—not indicated—through the air valve to a closed tank and thence through a flushing valve to a toilet—the air valve being also connected with a drain pipe.

Figure 2 is a vertical cross-sectional view through the valve showing it closed against the passage of water and air to the compression tank.

Figure 3 is a similar vertical cross-sectional view through the valve, showing it open for the delivery of water and air to the tank.

Figure 4 is a cross-sectional view taken on or about line 4—4 of Figure 2.

Figure 5 is a cross-sectional view taken on or about line 5—5 of Figure 2.

Figure 6 is a cross-sectional view taken on or about line 6—6 of Figure 2.

Referring now to the letters of reference placed upon the drawings:

A denotes the body of the valve. B

indicates a cylindrical top cover having an outwardly projecting flange overlapping the wall of the valve body. C is a collar screwed upon the valve body having a flange overlapping the flange of the cover. D indicates a leather diaphragm, secured between the wall of the body and flange of the top cover provided with a port D¹.

E is the chamber of an air exit valve from which projects downwardly a screw-threaded neck E¹ integral with the valve seat E² within the chamber. F denotes the valve, which normally rests upon the seat E², guided by a plunger or stem projecting through a spider frame or wall E^a at the upper end of the valve chamber.

G is a spring resting upon a projecting flange of the chamber E and bearing at its upper end against a shoulder formed by the wall of the cover B, secured to the valve body. H denotes an air chamber loosely sleeved within the valve body open to and screwed to the neck E¹ of the air exit valve.

To the lower wall of the air chamber H is secured a valve washer I by a thimble J having a limited vertical movement through a central bore in the partition wall A¹ dividing the body of the valve into two chambers.

J^a denotes transverse ports in the annular wall of the thimble through which water enters the air chamber by way of the water inlet K from the piping L leading to the source of supply—see Figure 1.

K^a is a plug valve screwed into a neck K¹, integral with the water inlet K, to control the flow of water through the latter. K^b is a closure cap for the end of the neck.

M is a drain pipe connection, screwed to a drain pipe M^a—see Figure 1—secured by a collar N to the lower end of the valve body. P denotes the body of both a relief and a drain valve, having a flange P¹ fitted with a gasket extending between the flange of the drain pipe connection and the body of the valve to which it is secured by the collar N.

Q denotes a drain valve of cup-plunger type adapted to close a transverse port Q¹ 100

through the wall of the valve body P which is spaced—as indicated at P^a—from the wall of the main valve to provide a passage to the port Q¹ opening into the cup-plunger Q 5 when the latter is open.

Q^a is a spring lodged within the plunger bearing against the upper wall of the plunger at one end and at the other end upon a washer Q^b, forming a valve seat encircling a 10 port Q², extending downwardly through the valve body. Q^c is a screw, screwed into the wall of the valve body, the head of which overlaps the valve Q—see Figures 2 and 4—to limit the upward movement of the valve.

15 R indicates a cup-shaped pressure relief valve seated upon a tubular stem R¹—see Figures 3 and 4—leading to a chamber R², open below in the body P. The valve R is mounted upon a rocking frame S—see Figure 4—pivoted upon a transverse bar S¹ supported by posts R², R³, integral with the body.

20 R^a is a washer mounted in the cup-shaped valve R, and R^b is an adjusting screw in the cup-shaped valve for adjusting the washer. S² is an arm integral with the frame S, which projects into the path of the thimble J, extending downwardly from the air chamber, which in its lowermost position—see Figure 2—serves to trip the arm S², as will be hereafter explained. S³ denotes a spring bearing against the arm to yieldably maintain it in its normally elevated position.

25 35 Screwed into the outlet in the top of the cover B is a pipe T leading into a T connected by a nipple with the bottom of a hydro-pneumatic tank U, and T^a is a pipe leading from the T to a flush valve V controlling the delivery of water to the toilet bowl W—see Figure 1.

Having indicated the several parts by reference letters, the construction and operation of the device will be readily understood.

40 45 For the purposes of this description it will be assumed that it has been installed in connection with a pressure tank for delivery of water to a toilet bowl as disclosed in Figure 1 of the drawings.

50 55 It should be understood that the main valve I and exit valve F are normally closed when no water is flowing through the valve, and that the drain valve Q and relief valve R are normally open.

60 65 The main valve is activated by relieving the water pressure on the upper face of the diaphragm D either by opening a tap connected with the supply pipe attached to the outlet from the valve, or the supply leading into a hydro-pneumatic tank, or in any other similar manner.

When the pressure is relieved as indicated, the water entering at the inlet K exerts pressure on the lower face of the diaphragm D and thereby opens the main valve I, which

upon raising allows the relief valve R to close. The water instantly flows into the lower chamber of the main valve and exerting its pressure upon the upper face of the drain valve Q, closes that valve.

70 The running water also passes through the ports J^a in the thimble J, into the air chamber H forcing the air therein out through the exit valve F and thence into the water system leading to the storage or hydro-pneumatic tank.

75 The valves remain in this position as long as the water continues to flow freely due to the fact that the pressure is greater on the underside of the diaphragm.

80 When the flow of water is terminated or nearly terminated through the closing of a faucet in the supply, or as a result of the gradual filling of a storage tank having air therein, the main valve closes, owing to the pressure on both sides of the diaphragm D becoming equalized.

85 The closing of the main valve opens the relief valve R and the water pressure closes the exit valve F, preventing any further water entering the air chamber H, thereby effectually relieving the pressure on the drain valve Q which is now forced open by the spring Q^a therein.

90 95 The water in the air chamber H now drains into the lower valve chamber, thence through the drain port Q¹,—through the opening Q² and out through the bottom of valve where a drain pipe M^a is connected to carry the water by gravity to any desired point.

100 105 The port D¹ in the diaphragm D is to provide means whereby the pressure on the upper and lower faces of the diaphragm may be equalized after the main valve I has automatically closed.

110 As the valve becomes operative each time the pressure is relieved, it is obvious that one valve may be employed to take care of two or more pressure tanks, for example, if the pressure tanks are employed to flush closet bowls, the valve may be installed in a main line to which are connected branches leading to two or more tanks, the air will pass to the particular tank leading to a particular bowl, at the time of each flush. The same result is attained with air chambers in connection with individual faucets, as the air would be carried to the particular air chamber connected with each faucet, every time any faucet was opened.

115 Having thus described my invention what I claim is:

120 125 1. In combination with a water system including means for intermittently drawing water from the system, a device of the character described, comprising a valve body provided with an inlet and an outlet port; a combined main valve and air chamber within the valve body, adapted to be actuated

by the pressure of the water flowing through the valve body, whereby when water is withdrawn from the system through the valve body, the air within said air chamber is automatically injected into the water passing through the valve body.

2. In combination with a water system equipped with means for intermittently drawing water therefrom, a device of the character described, comprising a valve body provided with an inlet port and an outlet port; an air chamber within the valve body; a valve adapted to normally prevent water from entering the air chamber, and also adapted to be actuated by the pressure of water flowing through the valve body, whereby when water under pressure flows through the valve body, the air within said valve body is automatically injected into the water passing through the valve body.

3. In combination with a water system including manually operated means for drawing water from the system, a device of the character described comprising a valve body provided with a partition dividing the body into upper and lower chambers with a bore and main valve seat in the partition; a combined main valve and air chamber within the body adapted to be actuated by the pressure of the water flowing through the valve body, whereby upon withdrawing water from the water system the contents of the air chamber automatically pass through the valve body.

35 4. In a device of the character described, a valve body provided with a partition dividing the body into upper and lower chambers with a central bore and main valve seat in the partition; a combined air chamber and main valve normally seated in said partition, with a depending neck extending through its central bore into the lower chamber; a diaphragm secured in the valve body; an exit valve; an annular connection between the exit valve and air chamber, extending through the diaphragm; a pressure relief valve; a drain valve; and suitable water inlet, discharge and drainage connections through the wall of the valve body.

50 5. In a device of the character described, a valve body; a partition wall having a central bore and main valve seat dividing the body into upper and lower chambers; a water inlet leading to the upper chamber; a cylindrical cover mounted on the wall of the upper chamber; a diaphragm secured between the cover and upper chamber; an air exit valve chamber located above the diaphragm having a depending neck projecting through an opening in the diaphragm; a combined air chamber and main valve secured to the depending neck of the air exit valve; a sleeve extending from the lower wall of the combined air chamber and main valve through a bore in the partition wall, said

sleeve having transverse ports for the passage of fluid into the air chamber; a pressure relief valve in the lower chamber of the valve body adapted to be raised by the downward thrust of the depending thimble of the combined air chamber and main valve, when the main valve is seated; and a spring actuated drain valve adapted to be automatically closed by the pressure of the incoming water when the valve carried by the air chamber is raised and to automatically open under the urge of the spring when said main valve is closed.

6. The combination of a valve body divided by a partition, having a central bore and a main valve seat, forming an upper and lower chamber; a water inlet leading to the upper chamber; an annular cover mounted on the wall of the upper chamber, tapped at its upper end for a pipe connection; a diaphragm secured between the walls of the valve body and cover; an air exit valve chamber and valve located within the cover having a neck projecting downwardly through the diaphragm; a combined air chamber and main valve secured to said neck, normally resting upon the main valve seat in the partition dividing the valve body; an annular neck extending downwardly from the air chamber through a central bore in the partition wall, having transverse ports through its wall; a pressure relief valve in the lower chamber of the valve body, automatically actuated through the vertical downward thrust of the neck of the air chamber, when the main valve is seated; a drain valve adapted to be automatically closed by the pressure of the incoming water, when the combined main valve and air chamber is raised, due to excess pressure of water against the underside of the diaphragm; and means for automatically opening said valve when the pressure above and below the diaphragm is equalized.

In testimony whereof, I sign this specification.

FREDERICK A. SCHLOSSOW.
